WHISTLING WHIRLING TOY

Louis S. Spallone, Denver, Colo.

Application January 18, 1950, Serial No. 7,316

Term of patent 14 years

(Cl. D34—15)

To all whom it may concern:

Be it known that I, Louis S. Spallone, a citizen of the United States of America, residing at Denver, in the county of Denver and State of Colorado, have invented a new, original, and ornamental Design for a Whistling Whirling Toy, of which the following is a specification, reference being had to the accompanying drawing, forming a part hereof.

In the drawing:

Fig. 1 is a front view of a whistling whirling toy, showing my new design;

Fig. 2 is a side view thereof; and

Fig. 3 is an end view thereof.

The opposite end has the same appearance as the end shown in Fig. 3.

I claim:

The ornamental design for a whistling whirling toy, as shown.

LOUIS S. SPALLONE.
